UNITED STATES PATENT OFFICE.

JOSEF BAUMGARTEN, OF NEW YORK, N. Y.

ELASTIC ATTACHMENT FOR NECKTIE-BANDS.

SPECIFICATION forming part of Letters Patent No. 556,729, dated March 24, 1896.

Application filed June 25, 1895. Serial No. 553,958. (No model.)

To all whom it may concern:

Be it known that I, JOSEF BAUMGARTEN, a citizen of the German Empire, and a resident of New York, county of New York, State of New York, have invented certain new and useful Improvements in Elastic Attachments for Necktie-Bands, of which the following is a specification.

The object of my invention is to provide an elastic attachment for necktie-bands of simple and cheap form of construction, but of extreme durability, which may, if desired, also form the fastening or clasp of the band; and to these ends my said invention consists of the construction, combination and arrangement of the several parts thereof shown and described in the following specification, of which the accompanying drawings form a part, wherein similar letters and numerals of reference designate like or equivalent parts wherever found throughout the several views, and in which—

Figure 1 is a back view of a necktie provided with my improved form of necktie-band elastic attachment and fastener as the same appears when secured to the necktie-band proper and in position upon the neck of the wearer. Fig. 2 is a like view in detail of such attachment and fastener removed from the band proper of the necktie, and Fig. 3 is an end view in section on the line $y-y$ of Fig. 2 of the coil-spring forming the elastic portion of such device.

While not limited to such use, this attachment is more particularly designed and adapted for use with neckties of the particular form known as the "bow" or "full-dress" necktie.

In the drawings the reference-numeral 1 designates the left-hand and 2 the right-hand side portion of the band proper of the necktie, while A designates the elastic attachment, and B the bow or *i.e.*

The main portion of the attachment A is composed of a coil-spring 3, formed of suitable spring-wire, and such spring is preferably in cross-section of the flattened or oblong shape shown in Fig. 3.

The spring 3 is preferably provided at one end with a loop or other suitable device 4 to facilitate the securing thereto of the end of the necktie-band on one side, and the spring 3 is

preferably provided at its other end with a ring or hook 5, adapted to slip over a suitable hook 6, which is secured to the end of the necktie-band in any desired manner, preferably by being sewed thereto by threads passing through holes 7 formed for that purpose in the back plate 8 of such hook 6, as shown in Fig. 2. The spring 3 is preferably provided at or near the center thereof with a button-loop 9, preferably formed, as shown, by extending the wire of which the coil is composed parallel with the axis of the coil at the bottom thereof for a short distance, say a half an inch or so, and then continuing the formation of the coil as before, such button-loop 9 being preferably located, as shown, in the center of the spring 3, so that when the necktie is in place upon the wearer the straight wire forming the bottom of the button-loop 9 will rest underneath the head of the back collar-button 10, as shown in Fig. 1, by which arrangement upward displacement of the attachment and of the necktie-band will be absolutely prevented.

While my improved form of elastic attachment may be used in other positions, I prefer to locate the same exactly opposite to the tie and in the center of bands of equal length; but in any event the bands and spring are of such length that when in position on the neck of the wearer the spring will be under sufficient tension to hold the necktie firmly in place.

The coil-spring 3 may be formed of any suitable material, but is preferably of brass or steel wire, and when to be used with dark-colored goods such wire is preferably japanned, and with white nickelated. The loop 4 and hook 5 are preferably formed integral with the spring 3 by simply bending and twisting the ends of the wire forming such spring into the shapes required to form such loop and hook.

The end portions 1 and 2 of the necktie-band, the rest of which is formed by the spring attachment A, are each preferably provided with suitable means for quickly and easily regulating the length thereof, so as to keep the button-loop 9 in the central position to engage with the rear collar-button; but inasmuch as such devices are well known in the

art and form no part of this invention I have not deemed it necessary to show or describe the same herein.

The attachment A being located exactly opposite to the bow or tie, and the entire band, of which such attachment forms a part, being of the length required; the bow or tie is secured upon the neck of the wearer by passing the loose ends of the attachment and band around the neck from the front and slipping the ring 5 over the hook 6, when the tension of the spring will serve to hold the tie in place, while admitting of perfectly free movement of the neck and throat.

It is evident that many changes may be made in such necktie attachment and fastener without departing from the scope of my invention, and I do not intend to limit myself to the exact construction shown; but,

Having now particularly described and ascertained the nature of my said invention and in what manner the same is to be performed,

what I claim, and desire to secure by Letters Patent, is—

In an elastic necktie-band attachment and fastening, the combination with a coil-spring 3 of oblong form in cross-section and having a button-loop having a bottom bar substantially in line with the lower edge of the spring-coil, of means for permanently securing one end of the spring to one portion of the necktie-band, and means for detachably securing the other end of the spring to the other portion of the necktie-band, substantially as shown and described.

In testimony that I claim the foregoing as my invention I have signed my name, in presence of two witnesses, this 6th day of June, 1895.

JOSEF BAUMGARTEN.
